(57) **CLAIM**

The ornamental design for a sneeze guard with shelf, as shown and described.

DESCRIPTION

FIG. 1 is a perspective view of a sneeze guard with shelf, showing our new design;

FIG. 2 is a left side view, thereof, the right side view thereof being a mirror image;

FIG. 3 is a front elevational view, thereof;

FIG. 4 is a rear elevational view, thereof;

FIG. 5 is a top plan view, thereof;

FIG. 6 is a bottom plan view, thereof;

FIG. 7 is a perspective view of an alternate embodiment of the sneeze guard with shelf;

FIG. 8 is a left side view, thereof, the right side view thereof being a mirror image;

FIG. 9 is a front elevational view, thereof;

FIG. 10 is a rear elevational view, thereof;

FIG. 11 is a top plan view, thereof; and,

FIG. 12 is a bottom plan view, thereof.
